UNITED STATES PATENT OFFICE.

GEORGE F. HUGHSON, OF CHICAGO, ILLINOIS.

REDUCING-VALVE.

SPECIFICATION forming part of Letters Patent No. 634,001, dated October 3, 1899.

Application filed January 26, 1898. Serial No. 667,957. (No model.)

To all whom it may concern:

Be it known that I, GEORGE F. HUGHSON, residing at Chicago, in the county of Cook and State of Illinois, have invented certain new and useful Improvements in Reducing-Valves, of which the following is a specification.

The object of this invention is the production of a reducing-valve of few and simple parts, and wherein those parts are not likely to become clogged or to get out of order.

In the accompanying drawings, Figure 1 is a vertical central section of this reducing-valve. Fig. 2 is a longitudinal section of the valve proper, and Fig. 3 is a transverse section of the same.

Like letters of reference indicate corresponding parts throughout the several views.

A is the outer shell of the reducing-valve, being a casting made in suitable form.

A' is a steam-inlet port having communication with the boiler.

A² and A³ are coinciding openings through the walls of the port A'.

A⁴ is an opening through the outer shell of the valve in vertical alinement with and of equal size to the openings A² and A³.

A⁵ is a chamber, and A⁶ an outlet-port for the steam under the reduced pressure of the low-pressure system.

B is a valve capable of a longitudinal movement through the alined openings A² A³ A⁴, also free to turn in said openings. This valve has the upper cylindrical portion B', the middle webbed portion B², composed of three vertical vanes, the two valve-closures B³, the lower webbed portion B⁴, also composed of three vertical vanes, and the lower stem portion B⁵.

B⁶ is a slight depression in the upper end of the valve B. The valve-closures B³ are of such size and so arranged as to just coincide with the openings A² and A³, thus closing the valve.

C is a bushing screwed onto the upper portion of the shell A, having the central opening C', extending in alinement with the openings A², A³, and A⁴.

C² is a headed stud lying within and adapt-

ed to fit said opening C', the lower end of the 50 stud resting within the depression or seat B⁶, formed in the upper end of the valve B.

C³ is a condensing-chamber, and C⁴ a drip-pipe therefor having communication with the outer air.

55 D is a coiled compression-spring. D' is a housing for said spring, and D² is a hand-wheel having a screw-threaded shank D³ with a headed end for engaging and applying pressure to said spring D. The spring D thus 60 lies within the housing D' between the stud C² and the headed shank D³ of the hand-wheel D², tension being applied to the spring by turning the said hand-wheel.

D⁴ are air-ports through the walls of the 65 housing D'.

In the practical application of this device the port A' is connected by a pipe with the boiler and the steam-outlet A⁶ with the low-pressure system. The spring D is set by the 70 hand-wheel D² with reference to the pressure which it is desirable to carry in the low-pressure system, and the spring A, pressing upon the stud C², pushes the valve B downward, opening it to its full extent. Steam from the 75 boiler under high pressure passes through the valve B and into the low-pressure chamber A⁵, but does not disturb the position of the valve.

When the pressure in the low-pressure system rises to the point for which the 80 spring D is set to operate, the said spring is compressed by that pressure and the valve B closes the port A'. The port remains closed until the pressure in the low-pressure system falls below the pressure for which the 85 spring D was adjusted, when the force of the spring overcomes the pressure of said system and the valve B is pushed open to admit more high-pressure steam. It will thus be seen that the valve B is a balanced valve, having 90 atmospheric pressure and the pressure of the spring D at its upper end pressing downward and tending to open it and the pressure of the steam in the low-pressure system exerted upward upon the piston area formed by 95 the lower end of the cylindrical portion B' of the said valve B tending to close the valve.

The steam in passing through the valve B im-

pinges on the vanes B' and B^2 and tends to turn the valve in its seat, making the wear equal on all sides thereof.

The tension of the spring D may be adjusted to permit any pressure desired in the low-pressure system, and this regardless of variations in the boiler-pressure.

I claim—

In a reducing-valve, in combination, a valve-shell, a steam-inlet pipe projecting within said shell having two aligned openings through its walls, a low-pressure chamber within the valve-shell, a condensing-chamber, and a spring-housing aligned with said openings in the inlet-pipe, which low-pressure chamber, condensing-chamber and spring-housing have intercommunicating openings in their walls, a cylindrical valve for the aligned openings in the inlet-pipe capable of a longitudinal movement therein, which valve

has a stem for resting on the valve-shell when the valve stands open; also has a portion of its surface removed to permit the passage of steam when the valve is open, and a cylindrical portion with a countersink in the end thereof, which cylindrical portion extends within and closes the opening between the condensing-chamber and the low-pressure chamber, a coil-spring in the housing, a hand-wheel for adjusting the tension of said spring, 25 a stud fixed on one end of said spring, which stud extends through and closes the opening between the housing and the condensing-chamber, an opening from the condensing-chamber, and a steam-outlet.

GEORGE F. HUGHSON.
